UNITED STATES PATENT OFFICE.

EDGAR KIDWELL, OF MILWAUKEE, WISCONSIN.

BAFFLE FOR WATER-TUBE BOILERS.

1,349,574.

Specification of Letters Patent. Patented Aug. 17, 1920.

Application filed August 5, 1919. Serial No. 315,401.

To all whom it may concern:

Be it known that I, EDGAR KIDWELL, a citizen of the United States, and resident of Milwaukee, in the county of Milwaukee, and State of Wisconsin, have invented certain new and useful Improvements in Baffles for Water-Tube Boilers, of which the following is a specification.

This invention relates to baffles for water-tube boilers of the series drum and tube type, and particularly baffles which are located within and longitudinally of the rearward bank of water tubes in order to provide downward and upward passes for the products of combustion among said tubes.

The object of my invention is to provide a metal baffling of simple, cheap, durable and efficient construction which can be readily applied to or removed from the interior of the rear tube bank, without the necessity of tearing down a portion of the brick wall or otherwise disturbing the boiler setting.

In the preferred form of embodiment of my invention, I construct the body of the baffle of a series of longitudinally flanged or trough-like sections, which are stamped or otherwise fashioned from sheet metal, and are adapted to be arranged within the spaces between adjacent pairs of inner water tubes in such a manner that the longitudinal flanges of the sections will contact with the proximate tubes without impairing the heating surface of the latter; and I provide novel means whereby the said plates can be readily, though detachably, clamped in place, all as will be hereinafter fully described and claimed.

In the drawings—

Fig. 1 is a vertical section through a rearward bank of tubes and the drums connected thereby, showing my improved baffle in position.

Fig. 2 is a partial vertical section of the structure, in a plane at right angles to Fig. 1.

Fig. 3 is a horizontal section through a series of the tubes and the baffling, as on the line 3—3 of Fig. 1.

Fig. 4 is a perspective view, partly in section, of one of the baffle sections, showing a bolt and clip device therefor.

Fig. 5 is an elevation enlarged, of one end of a baffle section, showing the bolt head as

entered in the elongated opening of the section.

Referring to the drawings, 10 designates one of the upper steam-and-water drums of a steam boiler of the series drum and tube type; 11 the underlying mud drum, and 12, 13 the rear bank of approximately vertical tubes which connect the upper drum with the mud drum. This bank of tubes is medially divided throughout the width of the boiler by baffling which extends down from the upper drum and terminates short of the mud drum, to afford downward and upward passes for the products of combustion among the tubes, as such products travel to the rearward breeching or smoke stack of the structure.

The baffling, in the preferred form of my invention, comprises rows of elongated metal sections 14 having longitudinal marginal flanges 15 which are outwardly flared or inclined as shown; the width of each section being such that when it is disposed longitudinally of and between two adjacent inner tubes 13, the flanges 15 laterally contact with the respective tubes, as seen most clearly in Fig. 3; thus bridging the space between said tubes. Hence by arranging a series of the sections end to end the space may be closed throughout any desired part of its length. The body of each trough-like section has formed therein, at spaced intervals, transverse recesses 16 which are intersected by elongated rectangular openings 17 extending longitudinally of the section. The sections are securely but detachably held in place within the tube bank by T-head bolts 18, the heads 19 of which are snugly seated in the recesses 16, while their shanks extend forwardly through the spaces between the adjacent tubes 13 of the bank, and carry at their outer ends perforated clips 20 having inclined flanges which are clamped hard against the opposing front tubes by means of nuts 21 on the screw-threaded outer ends of the bolts. The clip flanges are inclined reversely of the section flanges, and hence when the nuts are screwed home, the flanges of the respective elements coöperate with the opposing tubes to prevent lateral displacement of the sections.

The sections 14 are arranged in parallel rows to cover to the desired extent the suc-

- ceeding spaces between the interior tubes of the bank throughout the width of the boiler, thereby providing an efficient baffle in the path of the products of combustion.
- 5 The uppermost baffle sections, 14', located adjacent the drum 10 are curved correspondingly with the upper ends of the water-tubes; one of such curved sections and two straight sections being preferably used for 10 each space between a pair of the tubes. Each curved section is relatively short and a single connecting bolt therefor is sufficient.
- 15 The baffle sections above described comprise steel plates which are readily and cheaply formed and stamped in a die press. It will be seen that the several sections can be readily applied to or removed from the interior of the rearward tube bank from the forward side of the latter. To apply a 20 section, it is introduced edgewise between the forward tubes 13 of the bank, that is, at right angles to the vertical plane of the baffle, and is then positioned to bridge the space between the adjacent inner tubes. The T- 25 head of one of the bolts is then inserted from the front through a rectangular opening of the section, and is turned a quarter-turn and seated in the proximate recess. The clip is then turned to bridge the space 30 between the adjacent pair of front water tubes, and the nut is screwed hard against the clip so as to clamp the latter and the complementary section against the respective opposing tubes. The other bolt and its 35 adjuncts are then similarly applied and manipulated. To remove the sections, or any of them, for renewal or repair of the same or of a tube or tubes, a reverse operation to that above described is followed.
- 40 The recesses in which the bolt-heads are seated prevent the bolts from turning when the nuts are being slackened, particularly in the event of the rusting of the nuts after the boiler has been in use. When the boiler tubes 45 are spaced alternately wide and narrow, as shown, two appropriate widths of flanged sections are employed.
- 45 Inasmuch as the temperature at the rear of the boiler is relatively low the trough 50 sections may be made comparatively thin without danger of their burning out; and since the flanges of said sections do not encircle the tubes, but merely touch them in straight lines extending longitudinally of the tubes, the heating surface of the tubes is 55 unimpaired.

Without limiting my invention to the specific details of construction herein disclosed, what I claim is—

1. In a boiler of the series drum and tube type, the combination with the rearward bank of water-tubes, of a series of baffle sections arranged within the spaces between adjacent pairs of inner tubes of the bank, each of said sections comprising an elongated plate having longitudinally-extending inclined marginal flanges and an elongated opening, the inclination of the flanges adapting the plate to be seated against two tubes and to extend therebetween, a bolt having its head adapted to be passed through said opening and engage the plate, and its shank to extend forward of the tube bank, a clip on said shank bearing against a pair of front tubes of the bank, and a clamp-nut 75 on the bolt coöperating with the said clip.

2. In a boiler of the series drum and tube type, the combination with the rearward bank of water-tubes, of a series of baffle sections arranged within the spaces between adjacent pairs of inner tubes of the bank, each of said sections comprising an elongated plate having longitudinally-extending inclined marginal flanges, and having a transverse recess, and an elongated opening 85 intersecting the recess, the inclination of the flanges adapting the plate to be seated against two tubes and to extend therebetween, a clamping bolt having its head adapted to be passed through said opening 90 and seated in said recess, a clip on said bolt bearing against two adjacent tubes, and a nut on said bolt coöperating with the clip.

3. The herein described baffle section for water-tube boilers, comprising an elongated plate of sheet metal having longitudinally-extending inclined marginal flanges, and having a transverse recess, and an elongated opening intersecting the recess, the inclination of the flanges adapting the plate to be 100 seated against two tubes and to extend therebetween, a clamping bolt having a T-head adapted to be passed through said opening and seated in the recess, a clip on said bolt bearing against two adjacent tubes, and a 105 screw-nut on said bolt coöperating with the clip.

Signed at Milwaukee, in the county of Milwaukee, and State of Wisconsin this first day of August, A. D. 1919.

EDGAR KIDWELL.
